UNITED STATES PATENT OFFICE.

WILLIAM H. CARY, OF BROCKTON, MASSACHUSETTS, ASSIGNOR TO AVON SOLE COMPANY, OF AVON, MASSACHUSETTS, A CORPORATION OF MASSACHUSETTS.

SHOE.

Application filed June 29, 1923. Serial No. 648,459.

REISSUED

To all whom it may concern:

Be it known that I, WILLIAM H. CARY, a citizen of the United States, and resident of Brockton, county of Plymouth, State of Massachusetts, have invented an Improvement in Shoes, of which the following description, in connection with the accompanying drawing, is a specification, like characters on the drawing representing like parts.

10 This invention relates to improvements in shoes and shoe soles and also in the process of forming the sole and attaching the sole to the shoe. The general object thereof is to provide a shoe having a plastic sole which 15 will more securely be retained on the bottom of the shoe.

Heretofore certain shoes of this type have been made with the plastic sole sewed directly to the welt of the shoe but this proved 20 to be unsatisfactory because if the sole was soft enough to give desirable qualities to the shoe it was so soft that the stitches which held the sole on the shoe would pull through the tread and permit it to easily break away 25 from the shoe. Also the soft plastic sole permitted the welt of the shoe to spread and the alternate spreading and contracting as the wearer walked, besides being uncomfortable, soon caused the stitches to cut through 30 the plastic tread. If the usual stiff leather whole sole is used for a shoe, the base sole holds the welt together, since it is fairly stiff and non-extensible, but in the case of a shoe having a plastic tread member, which is 35 desirable, particularly in sport shoes, some means must be provided to take the place of the leather sole and perform its function in keeping the welt from spreading and the bottom of the shoe in the correct shape.

40 In other shoes of this type, a leather base sole was provided which covered the bottom of the shoe, formed an anchorage for the stitches which connected the same to the welt, and held the bottom of the shoe in 45 shape by holding the welt together. The plastic tread member was fastened on the outside of the leather base sole and the stitches went through the plastic tread member of the sole and through the leather anchoring or base member and then through 50 the welt of the shoe to hold the sole on the bottom of the shoe. In order to assist in retaining the tread member on the leather base

member a cement was used on the adjoining surfaces of the leather base member and the 55 tread unit but, because of the different natures and compositions of the tread member and the base member, the union was not satisfactory. If a cement was used which would stick to the tread unit it would not adhere to the leather base member and if a cement was used which would stick to the leather base member it would not stick sufficiently to the tread member to keep the 60 tread member from breaking away from the 65 leather base member. The stitches, as above-mentioned, would hold the tread member to the leather base member for a short period of time but would finally pull through the tread member and permit the 70 sole to part from the welt of the shoe. When the tread member parts from the leather base member even a slight distance at a single point, water is permitted to enter between the base member and the tread member, and this opening allows the rubber to 75 work and the stitches to cut through. The edge of the leather base member is usually glazed to prevent water from entering the 80 interior of a leather base member from the edge, but the flat surface of the leather base member is usually unglazed and if water is permitted to get into the sole of the shoe next to the leather base member between said 85 member and the tread, the dampness gradually spreads until the whole leather base sole is more or less damp depending upon the amount of water which gets in. The water causes the cement which sticks the tread member to the leather base member to 90 deteriorate and thus shortens the time that the tread member will be held on the leather base member by the adhesion of the cement. Further than this, the leather base member is usually made from split leather, which is 95 more or less in layers and is of such loose texture that even though the cement which is used to stick the tread member to the base member firmly joins the two members, the layer of leather which is permeated by the 100 cement easily pulls away from the remainder of the leather base member and allows the tread member to part from the shoe.

One of the objects of the present invention is to overcome the difficulties which are 105 present in the usual type of shoe above de-

scribed. This is done by providing a tough substantially non-extensible base member which performs the function of the leather base member but which has none of the disadvantages of the leather.

Another object of the invention is to provide a novel base member. The base member is preferably of such a composition that the tread member or tread unit may be caused to cohere therewith and to this end the base member is so made that it partakes of the composition of the tread unit. If the tread unit is of plastic crude rubber, the base member is preferably of a vulcanized rubber and fibre composition.

Another object of the invention, therefore, is to provide a shoe with a novel unitary sole. With a base member having a composition partaking of the nature of the tread unit a cement may be used to cement the tread unit to the base member which, because of the likeness of the composition of said unit and member, will cause the tread unit to securely and irremovably cohere to the base member. The union between the tread unit and the base member is one of cohesion, rather than adhesion which is the case if a rubber tread unit is cemented to a leather base member. A rubber cement is used which dissolves part of the rubber on the surface of the tread unit and part of the rubber on the composition base member and when this cement dries there is an interlocking of the molecules of the rubber on said unit and member which causes the two to be inseparably joined. The union may be further strengthened by an application of heat to the tread unit during the cementing process so that the tread unit is vulcanized to the base member. A vulcanized rubber and fibre composition base unit is especially desirable because it is waterproof and if by any chance water does get in between the base member and the tread unit due to an imperfect joining of said union and member around the edges of the sole, the water will not cause deterioration of the base member. The rubber cement which can be used in joining the rubber tread unit to the rubber composition base unit is unaffected by water so that even if the entire sole be subjected to the influence of water it will not deteriorate in any manner.

Another object of the invention is to provide a novel process for producing a shoe having a unitary, waterproof sole in which the stitches which secure the outer sole to the welt are embedded in the homogeneous material of the welt.

Other objects and features of the invention will more fully appear from the following description and the accompanying drawing and will be particularly pointed out in the claims.

The drawings illustrate in elevation a pre-

ferred form of shoe and shoe sole embodying the broad principles of the invention.

In the drawings:

Fig. 1 is a shoe with a preferred type of sole applied thereto;

Fig. 2 is an elevation of a shoe and sole therefor showing the sole in separated layers as they are fixed to the shoe.

In the preferred embodiment of the invention illustrated herein the shoe comprises an upper 1 and a welt 2 fastened to the upper and inner sole in the usual manner.

A heel seat 3 is fastened, preferably by nails 4, to the heel of the shoe in order to provide a projecting flange 5 around the heel as a continuation of the welt to which the sole of the shoe may be sewn.

The outer sole of the shoe comprises a base member 6 for joining to the welt of the shoe, an intermediate member 7, and a relatively thick tread member 8 having a heel 9 preferably formed integral therewith.

Although various materials may be used for the base, intermediate, and tread members, the base member is preferably of a waterproof composition, the tread member is preferably of plastic material, and the intermediate member is of the same composition as the tread member. The base member and intermediate member together form a base unit and since the intermediate member and tread member are of the same composition and form the actual tread of the shoe, they together may be termed the "tread unit".

The tread unit is preferably of a plastic material such as crude rubber and the base member for attaching the sole to the welt of the shoe, is of a rubber and fibre composition having such characteristics that it may be caused to cohere homogeneously

with the material of the tread unit by vulcanization or by the use of a cementitious composition containing a solvent for the plastic material of the base and tread member.

The fibre in the base member gives or assists in giving the base member the desirable property of being non-extensible so that it holds the welt and sole of the shoe together and the bottom of the shoe in shape

and the rubber constituent of the base member that causes said member to cohere so strongly with the material of the tread to give a unitary sole. The base member and intermediate member are made as a base unit for the purpose of permitting the base unit to be readily sewn to the welt of the shoe, and since the tread member may be caused to cohere so firmly to the base unit by means of the intermediate member after the base unit has been sewn to the shoe and on the outside of the stitching, the stitches are embedded in the homogeneous composition of the outer sole well beneath the surface thereof and are protected from the deteriorating effect of any moisture or dampness.

In making the sole and securing it to the

shoe a quantity of crude rubber is first moulded to form the tread member 8 and the intermediate member 7 of such an area that they will well cover the bottom of the shoe 5 and form a sole therefor. The base member is molded in the proper shape from a composition of rubber and fibre and is then vulcanized. The adjoining surfaces of the base member and the intermediate member are 10 then coated with a rubber cement having a constituent which is a solvent for the rubber of the sole and base member and when the cement has dried to such an extent that the surfaces are in the right condition for joining they are placed together and the base unit is then preferably placed in a heated vulcanizing press. The surface of the press which rests against the crude rubber intermediate member is heated so that when 15 pressure is applied, the intermediate member is not only cemented but vulcanized to the base member to form a base unit the layers of which are inseparable. The base unit therefore comprises a layer of fibrous 20 material with a facing of rubber cohering homogeneously to the fibrous material. If crude rubber is used for the intermediate member, a base unit may thus be formed comprising a layer of waterproof vulcanized rubber and fibre material with a facing 25 of crude rubber cohering homogeneously to the fibrous material. The base unit is then sewed by means of stitches 10 to the welt of the shoe with the fibrous material lying next 30 to the welt and the facing outermost. The outer surface of the intermediate member and the inner surface of the tread member are then coated with rubber cement containing 35 a constituent which is a solvent of the rubber and stuck together by means of pressure with or without the application of heat. When heat is applied the tread member is vulcanized to the intermediate member but in either case there is an interlocking of the 40 molecules of the rubber on the intermediate member with the molecules of the rubber of the tread member which causes a firm cohesion of the two which inseparably holds them together just as the intermediate member is inseparably held to the base member. 45

By carrying out the above process with the materials formed and in the condition above stated I am enabled to provide a 50 welted shoe comprising an outer sole having a base unit consisting of a layer of water-

proof vulcanized rubber and fibre material provided with a section of crude rubber cohering homogeneously to the fibrous material throughout its entire area stitched to the welt of the shoe, and a relatively thick tread 55 member of crude rubber cohering homogeneously to the facing. The parts of the sole are inseparably joined and the stitching which secures the sole to the welt of the shoe is embedded in the composition of crude 60 rubber well beneath the tread surface thereof thereby protecting the stitches from dampness.

I desire that the invention be construed as broadly as the limitations in the claims. 70

Having thus described the invention what is claimed as new and desired to be secured by Letters Patent is:

1. A welted shoe comprising a welt, a base unit consisting of an upper layer of a tough 75 substantially non-extensible homogeneous composition of fibre and rubber to maintain the shape of the shoe and form an anchorage for stitches and a lower layer of rubber cohering homogeneously to the upper layer 80 throughout its entire area, stitches passing through and uniting the welt and base unit and a relatively thick tread member of rubber cohering homogeneously to the lower 85 layer of the base unit throughout its entire area, whereby the base unit and tread member form an indivisible outer sole with the stitches embedded well beneath the tread surface.

2. The process of making a shoe which consists in providing a welted shoe upper, providing a base unit of an upper layer of a tough substantially non-extensible homogeneous composition of fibre and rubber to maintain the shape of the shoe and provide 90 an anchorage for stitches and a lower layer of rubber cohering homogeneously to the upper layer throughout its entire area, stitching the base unit to the welt with the upper layer contacting with the welt, applying a relatively thick tread member of rubber to the lower layer of the base unit and causing the rubber constituents of the tread member and base unit to cohere homogeneously throughout their entire contacting 95 areas.

In testimony whereof, I have signed my name to this specification.

WILLIAM H. CARY.
